UNITED STATES PATENT OFFICE.

WALTER A. YAEGER, OF ST. LOUIS, MISSOURI.

CLOSURE.

Application filed January 2, 1925. Serial No. 80.

To all whom it may concern:

Be it known that I, WALTER A. YAEGER, a citizen of the United States, and a resident of St. Louis, Missouri, have invented an Improvement in Closures, of which the following is a specification.

This invention relates to caps, and with regard to certain more specific features, to caps for collapsible tubes and the like.

10 Among the several objects of the invention may be noted the provision of means for readily opening and closing a collapsible tube or the like, said means involving the use of no screw threads, and the provision of 15 a captive cover for such containers, which is cheaply and readily assembled as well as effective in operation.

The invention accordingly comprises the features of construction, combinations of 20 elements and arrangements of parts, which are exemplified in the description herein-after in connection with the accompanying drawings, and the scope of the application of which will be indicated in the following 25 claims.

In the accompanying drawings, in which is illustrated one of various possible embodiments of the invention,

Fig. 1 is a top plan view of the device 30 shown closed in full lines and partially open in the dotted lines;

Fig. 2 is a side elevation of Fig. 1;

Fig. 3 is a fragmentary vertical section taken on the line 3—3 of Fig. 2; and,

35 Fig. 4 is a vertical section showing the cap in open position.

Similar reference characters indicate corresponding parts throughout the several views of the drawings.

40 Referring now more particularly to Figs. 1 and 2 there is illustrated at 1 a collapsible tube of the conventional type, made of a relatively soft metal. Its closure or breast 3 by reason of its conical shape and thickness 45 is more rigid than the tube 1 itself, although made of the same metal.

The closure 3 is provided with a horizontal top surface 5 from which extends vertically and centrally thereof the short tube 50 or nozzle 7. The tube 7 serves the conventional purpose of ejecting material from the tube 1.

On one side of the conical closure 3, there extends upwardly a catch 9 from which extends horizontally toward the tube 7 a latch

arm 11. The under side of the arm 11 is convexly formed. The catch 9 and cover 3 are integrally formed.

On the opposite side of the conical closure 3 is integrally formed with the cover 3, a hinge member 13. The hinge member 13 comprises a bridge with a laterally elongated opening 15 there beneath.

The cap or cover 17, operable to close and open, comprises a dished cover piece 19, a lug 21 extending laterally from one side of an open rim 18 of said piece 19, and a hook 20 from the opposite side of said open rim 18. The top surface of the lug 21 is convexly formed. The straight line elements of 70 said surface run the length of the lug, and are adapted to be parallel to the straight line elements of the latch arm 11 when the cap is in closed position. The hook 20 is made narrower laterally, than the opening 15 and receives its rounded shape about the bridge piece 13, after insertion into the opening 15. The metal of the hook 20 is thinner than the opening 15, thus permitting a vertical hinging 75 action of the cap 17 on the bridge 13. 80

The cap 17 is preferably made of the same yielding metal as the tube 1.

It seats its rim portion 18 on the flat surface 5 of the tube closure 3, thereby sealing the tube. Its dished portion permits ample room within for the tube 7, and beside, permits sideward movement of the cap 17 on the surface of portion 5. (Fig. 1). This sideward movement can take place because there is the discrepancy between the width 90 of the opening of the bridge 15 and the width of the hook 20 of the cap 17. In fact the bridge and hook form a lost motion hinge 23.

The purpose of the lost motion in the hinge 23 is to permit swinging of the cap 17 to one side, on said hinge, before seating said cap's rim on the surface of portion 5.

After bringing the rim to a seat around the tube 7, the cap 17 is pivoted about its point of lost motion until engagement between the convex surfaces of the latch arm 11 and the lug 21 is brought about. Engagement between these parts takes place before the cap 17 reaches the central solid-line position shown in Fig. 1. It follows that when the cap 17 is forced to said central position by a slight pressure of the finger, that the cam action between the surfaces mentioned, forces, the cap 17 to a tight 110

seat on the surface of portion 5, while the lost motion hinge 23 serves as a fulcrum.

The entire cap is preferably made of the same soft material as the latch arm so that friction between the convex surfaces prevents a spontaneous reversal of the cycle of events described.

In order to open the tube the cap 17 is merely pressed sidewise with a finger, whereupon the convex surfaces of the latch arm 11 and the lug 21 disengage and said members are thrown out of vertical interference. The sidewise pivoting action takes place on the lost motion hinge 23. The cap 19 is then free to be raised. It pivots vertically also, on the said lost motion hinge 23.

The facility with which a tube may be opened is manifest.

The elements of the lost motion hinge 23 are so shaped as to hold the cover 17, captive when said cover is in open position, thereby preventing the loss of said cover.

The absence of threads in this device permits of its economical manufacture, and prevents the necessity for tedious rotation and aligning of threads when in use.

From the above it will be seen that the several objects of the invention are attained and other advantageous results achieved.

As many modifications of the embodiments above illustrated might be made without departing from the spirit or scope of the present invention, it is intended that the above description and accompanying drawings and claims shall be interpreted as illustrative and not in a limiting sense.

I claim:

1. In combination with a collapsible tube comprising a container, a breast, and nozzle therefor; a closure for said tube comprising a cap for said nozzle adapted to be seated on the said breast of the tube adjacent the base of said nozzle, a lost-motion hinge on the breast for the cap whereby the cap may rotate vertically or laterally about a point within said hinge, a latch arm on the breast, a lug on said cap adapted to engage said latch arm in such a way as to force said cap to said seat with said hinge acting as a fulcrum.

2. In combination with a collapsible tube comprising a container, a breast, and nozzle therefor; a closure for said tube comprising a cap for said nozzle adapted to be seated on the said breast of the tube adjacent the base of said nozzle, a bridge formed on the breast and a latch arm, said arm and bridge being on opposite sides of the nozzle, a curved extension on said cap loosely passing under the bridge whereby the cap may swing laterally or vertically on the bridge, a hook on the outer end of said extension whereby said cap is held captive, and a lug on the cap adapted to engage said latch arm to bring the cap to a closed position with respect to the nozzle.

cap adapted to engage said latch arm to bring the cap to its seat.

3. In combination with a collapsible tube comprising a container, a breast, and nozzle therefor; a closure for said tube comprising a cap for said nozzle adapted to close the nozzle, a bridge formed on the breast and a latch arm, said arm and bridge being on opposite sides of the nozzle, a curved extension on said cap loosely passing under the bridge whereby the cap may swing laterally or vertically on the bridge, a hook on the end of said extension whereby said cap is held captive, and a lug on the cap adapted to engage said latch arm to bring the cap to a closed position with respect to the nozzle.

4. In combination with a collapsible tube comprising a container, a breast, and nozzle therefor; a closure for said tube comprising a cap for said nozzle adapted to be seated on the said breast of the tube adjacent the base of said nozzle, a lost-motion hinge on the breast for the cap whereby the cap may rotate vertically or laterally about a point within said hinge, a latch arm on the breast, a lug on said cap adapted to engage said latch arm in such a way as to force said cap to said seat with said hinge acting as a fulcrum, said latch arm and lug being composed of materials with high coefficients of friction whereby the said arm and lug remain latched until parted by pressure.

5. In combination with a collapsible tube comprising a container, a breast and nozzle therefor; a closure for said tube comprising a cap for said nozzle adapted to close the nozzle, a lost-motion hinge on the breast for the cap whereby the cap may rotate vertically or laterally about a point within said hinge, a downwardly convex lug on said cap adapted to engage the latch, from the side, the convex portions meeting so as to force said cap to said seat with said hinge acting as a fulcrum.

6. In combination with a collapsible tube comprising a container, a breast, and nozzle therefor; a closure for said tube comprising a cap for said nozzle adapted to close the nozzle, a lost-motion hinge on the breast for the cap whereby the cap may rotate vertically or laterally about a point within said hinge, a downwardly convex lug on said cap adapted to engage the latch, from the side, the convex portions meeting so as to force said cap to said seat with said hinge acting as a fulcrum and frictional surfaces on the convex portions whereby they cannot slip apart without side pressure being applied.

In testimony whereof, I have signed my name to this specification this 31st day of December, 1924.

WALTER A. YAEGER,
